US0D1035881S

(12) **United States Design Patent** (10) Patent No.: **US D1,035,881 S**
(45) Date of Patent: ** Jul. 16, 2024

(54) **OXYGEN CONCENTRATOR**

(71) Applicant: **ROAM TECHNOLOGIES PTY LTD**,
Summer Hill (AU)

(72) Inventors: **Shan-Shan Wang**, Sydney (AU);
Eugene Weng Hong Lai, Sydney (AU); **Natalie Etain Ho**, Sydney (AU)

(73) Assignee: **Roam Technologies Pty Ltd**, Summer Hill (AU)

(**) Term: **15 Years**

(21) Appl. No.: **29/841,196**

(22) Filed: **Jun. 3, 2022**

(51) LOC (14) Cl. **24-02**

(52) U.S. Cl.
USPC **D24/164**

(57) **CLAIM**

The ornamental design for an oxygen concentrator, as shown and described.

DESCRIPTION

FIG. 1 is a front elevation view of an oxygen concentrator showing the new design;

FIG. 2 is a rear elevation view thereof;

FIG. 3 is a right side view thereof;

FIG. 4 is a left side view thereof;

FIG. 5 is a top plan view thereof;

FIG. 6 is a bottom plan view thereof;

FIG. 7 is a front, top, left perspective view thereof;

FIG. 8 is a front, top, right perspective view thereof;

FIG. 9 is a front, bottom, left perspective view thereof;

FIG. 10 is a front, bottom, right perspective view thereof;

FIG. 11 is a rear, top, right perspective view thereof;

FIG. 12 is a rear, top, left perspective view thereof;

FIG. 13 is a rear, bottom, right perspective view thereof; and,

FIG. 14 is a rear, bottom, left perspective view thereof.

The dash-dash, broken lines illustrate portions of the oxygen concentrator that form no part of the claimed design.

1 Claim, 14 Drawing Sheets
